DESIGN FOR A SPORT JACKET

Harriet Hedin, Chicago, Ill., assignor to Reliance
Manufacturing Company, Chicago, Ill., a corporation of Illinois

Application August 10, 1935, Serial No. 58,066

Term of patent 3½ years

To all whom it may concern:

Be it known that I, Harriet Hedin, a citizen of the United States, residing at Chicago, in the county of Cook and State of Illinois, have invented a new, original, and ornamental Design for a Sport Jacket, of which the following is a specification, reference being had to the accompanying drawing, forming a part thereof.

Fig. 1 is a perspective front view of a sport jacket embodying my design; and

Fig. 2 is a perspective rear view of the sport jacket shown in Fig. 1.

I claim:

The ornamental design for a sport jacket as shown.

In witness whereof, I hereunto subscribe my name this 6th day of August, 1935, at Chicago, Illinois.

HARRIET HEDIN.
